UNITED STATES PATENT OFFICE.

LESLIE R. COFFIN, OF BELLINGHAM, WASHINGTON, AND REUBEN W. MASTICK, JR.,
OF SAN FRANCISCO, CALIFORNIA.

ELECTRIC ARC LAMP.

Application filed June 8, 1917. Serial No. 173,583.

To all whom it may concern:

Be it known that we, LESLIE R. COFFIN, a citizen of the United States, residing at Bellingham, in the county of Whatcom and State of Washington, and REUBEN W. MASTICK, Jr., a citizen of the United States, and a resident of San Francisco, in the county of San Francisco and State of California, have invented certain new and useful Improvements in Electric Arc Lamps; and we do hereby declare the following to be a full, clear, and exact description of the invention, such as will enable others skilled in the art to which it appertains to make and use the same.

This invention relates to improvements in electric arc lamps and more particularly to such as are especially adaptable for use in cinematographic, stereopticon or other projecting purposes.

One object of the present invention is to provide a projector type of electric arc lamp which will operate successfully with the use of a single-phase alternating current of commercial frequency without necessity for the use of auxiliary rectifying apparatus, and which may also be successfully and accurately operated with the use of unidirectional electric currents.

A further object is to provide, in an arc lamp of the type specified, simple and efficient means whereby the three electrodes employed, may be quickly and accurately adjusted with relation to each other and relatively to the projector lens.

A further object is to so arrange the electrodes and circuits of an electric arc lamp as to facilitate such rectification of the current employed as can obtain incident to the action of the arcs at the cooperating electrode terminals.

With these and other objects in view, the invention consists in certain novel features of construction and combinations of parts and circuits as hereinafter set forth and pointed out in the claims.

In the accompanying drawings; Figure 1 is a diagrammatical view showing the arrangement of electrodes and circuits when the lamp is employed with unidirectional currents; Figure 2 is a diagrammatical view showing the adaptation of the lamp for single-phase alternating currents; Figures 3 and 4 are views, partly in elevation and partly in section, of a lamp embodying the invention;

Figure 5 is a fragmentary sectional view showing the hinge connection between the parts of carrier 8^a, and Figure 6 is enlarged fragmentary sectional view showing the jack construction 37 for moving the upper part 60 of the carrier 8^b.

When the lamp is connected with unidirectional currents, an arrangement of three electrodes is provided so as to obtain a plurality of arcs. Resistances of desired constants are suitably disposed in circuit with the three electrodes and current supply terminals, for the purpose of regulating and maintaining the plurality of arcs formed between said electrodes. When the lamp is connected with single-phase alternating currents, an arrangement of three electrodes is provided so as to obtain a plurality of arcs, two of said electrodes being connected respectively by leads to the end terminals of the secondary winding of a single-phase alternating current supply transformer, and the third to the neutral or mid-point of said secondary winding of the single-phase supply transformer. Reactance coils of suitable constants may be placed in circuit with the leads connecting the three electrodes of the lamp to the secondary winding of the single-phase supply transformer, for the purpose of regulating and maintaining the plurality of arcs between said electrodes.

In the alternating current operation of the lamp, partial rectification of the alternating current supplied takes place. Hence the arcs produced in the three electrode lamp with alternating current are both unidirectional and alternating in character. When a proper overlapping of the successive half waves of current be produced, the rectifying action which obtains exerts a steady influence on the plurality of arcs between the cooperating electrodes.

The three electrodes are so arranged as to converge toward a common point and in addition to separate means of adjustment 100 for the electrodes individually, a pantographic structure is employed to obtain a simultaneous movement of the three electrodes toward the common point of convergence by the manipulation of one controlling rod. The advantage of an organization of this sort lies in the fact that the arc is always maintained at a sensibly constant distance from the projector lens. This will be readily understood when consideration is 110

given to the fact that as the arcs burn and the electrodes wear away, thus increasing both the distance from the arcs to the projector lens and the arc-gaps between electrodes, a slight adjustment of the pantographic control readjusts the arc separation between electrodes, and hence immediately restores the arc to its original position with respect to the projector lens.

10 Referring to Figure 1, 1, 2, 3 represent three carbon electrodes, the former of which are connected respectively through two resistances 4, 5 to a common point 7, which is the negative terminal of the "direct" current supply circuit. The third or central carbon 3 is connected with the positive terminal 6 of the "direct" current supply circuit. The three electrode arrangement results in the plurality of arcs being localized and forming a very hot crater at the positive electrode 3, giving a greater luminous intensity than is obtainable with the ordinary two electrode type of arc-lamp.

15 In addition, the arc is rendered very steady and requires little attention or adjustment, a feature of much importance in cinematograph apparatus.

20 In Figure 2, 1, 2, 3 represent the three carbon electrodes, the former of which are connected through two reactance coils 4, 5 respectively, to points 8, 9, representing the outer ends of the secondary winding of a single-phase alternating current supply transformer 9^a. The third carbon electrode 25 3 is connected through a reactance coil 6^a to the mid-point 7^a of the secondary winding 8, 9 of the single-phase alternating current supply transformer. When the single-phase alternating current supply transformer 30 is remote to the lamp, the neutral point 7^a of the single-phase circuit may be obtained by providing two balanced reactances disposed in series and bridged across the circuit at a point corresponding to 8, 9.

35 The reactance coils 4, 5 are inserted to provide an overlapping of successive half-waves of current essential to the continued excitation of the arc. The characteristics of these reactance coils are not specifically given, since they are determined by the required angle of overlap of the currents of successive half waves necessary to give the desired stability together with other factors which will vary with the capacity and usage of the lamp. Reactance coil 6^a of required characteristics is inserted in circuit between the points 3 and 7^a to maintain the voltage in said circuit above the counter E. M. F. of the arcs. With this arrangement, the alternating current supplied is in part rectified and the arcs are formed solely by successive half waves of current, between electrodes 1, 3 and 2, 3 respectively are unidirectional. The arcs occurring from electrodes 1 by 3 to 2 and 2 by 3 to 1 are alternating in character. The rectified part of the alternating current supplied, therefore, exists in the divided circuits indicated by 3, 6^a and 7^a. Owing to the high temperature of the carbon-arc and its consequent low voltage range of rectification, a complete rectification of the alternating current cannot take place such as would be possible with electrodes of lower temperature boiling points.

40 Electrode 3 is smaller than either electrodes 1 or 2 which fact promotes high incandescence of said electrode due to the passage of the arcs from 1 by 3 to 2 and from 2 by 3 to 1 in the case of alternating components of the arc current and from 1 to 3 and 2 to 3 respectively in the case of the unidirectional component of the arc current.

45 In the lamp shown in Figure 3, electrodes 1 and 2 are supported respectively by holders 4^b and 5^b carried by arms 6^b and 7^b, the latter being supported by the carriers 8^b and 9^b which are in turn supported by the pantographic structure 10, 11, 12 and 13. The electrode 3 is supported by holder 14 carried by arm 15, which is supported in the carrier 16, the latter being pivoted on the pantograph arms 12 and 13. In addition to being pivoted on the pantograph arms 12 and 13, the carrier 16 slides in a slot on the base 17. The two arms 10 and 11 of the pantograph are pivoted to a block 18 which also slides in a slot on the base 17. The block 18 is driven by the threaded rod 19 swiveled in a block 20 rigidly attached to the base 17. The upper and lower junctions of the pantograph arms 10, 12 and 11, 13 are pivoted by axles 21 and 22 passing through each pair and a slot 21^b in the carriers 8^b and 9^b respectively and thence extending into the slotted upright guides 21^a and 22^a (see Figures 3 and 4). Thus lateral movement of the upper and lower pantograph arm junctions is restrained, and hence operation of the rod 19 causes a recession or approach of the carriers 8^b and 9^b, and therefore, also, of the electrodes 1 and 2. By reason of the pantograph arms 12 and 13 being pivoted to the carrier 16 which is guided on the base 17, a recession or approach of the carrier 16 is caused and therefore, also of the electrode 3. Thus operation of the rod 19 causes contemporaneously a recession or approach of the three electrodes 1, 2, 3 toward a common point. The base 17 upon which rests the pantograph and associated carriers, arms, holders, etc., above described, is rigidly attached to a shaft 23 movable vertically in a holder by means of a rack and pinion gearing 25-26 controlled by a manually operable rod 27. The holder 24 is arranged to slide on two parallel rods 28, 29 usually provided in the lamp cabinet associated with commercial cinematographic machines.

50 The electrode holders 4^b, 5^b and 14 are in-

sulated from their carrying arms 6^b, 7^b and 15 by the insulated joints 30, 31 and 32 respectively, and in addition, pivot joints 33, 34 and 35 are provided between said insulated joints and the electrode holders 4^b, 5^b and 14 by which means additional angular adjustments of the three electrodes with respect to one another can be made, if desired.

The upper carrier 8^b is made of two parts, 10 the lower part being attached to the pantographic structure 10, 11, 12 and 13 in the manner previously described. The upper part is hollow so that the arm 6^b which supports the electrode holder 4^b and electrode 1 may 15 be caused to move axially forward or back independently of the carrier 8^b as operated by rod 19, by rotation of a threaded rod 36 swiveled in the upper part of the carrier 8^b and entering a threaded socket in the arm 20 6^b. Moreover the upper part of the carrier 8^b is hinged at or near one end to the lower part of said carrier 8^b by a pivot pin α and by means of the bevel gear and screw jack arrangement, 37, controlled by the manually 25 operable rod 38, can be caused to tilt up or down at one end, thereby raising or lowering the arm 6^b and, therefore, also the electrode 1. Rigidly attached to the arm 6^b is a spur gear 39 which meshes with another spur 30 gear 40 attached rigidly to a manually operable rod 41, resting in bearings attached to the upper part of the carrier 8^b, which can cause a radial movement of the arm 6^b with respect to its axis, and hence also cause a 35 radial movement of the electrode 1. A collar 42 is provided on the spur gear 39 which fits about the spur gear 40 so that the two gears remain meshed regardless of the position axially, of the arm 6^b controlled by the 40 rod 36.

The lower carrier 9^b is constructed in one piece attached to the pantographic structure 10, 11, 12 and 13 as previously described, and is hollow so that the arm 7^b which supports the electrode holder 5^b and electrode 2 45 may be caused to move axially forward or back independently of the carrier as operated by rod 19, by rotation of the threaded rod 43 swiveled in the carrier 9^b and entering a 50 threaded socket in the arm 7^b.

The central carrier 16 is hollow so that the arm 15 which supports the electrode holder 14 and electrode 3 may be caused to move axially forward or back independently 55 of the carrier 16, as operated by rod 19, by rotation of the threaded rod 44 swiveled in the said carrier 16 and entering a threaded socket in the arm 15. The threaded rod 44 in this case passes through and is supported by 60 the threaded rod 19.

The lamp and its electrodes will in all cases be adjustable with respect to the lens of the projecting apparatus, said lens being shown diagrammatically in Figure 3 and 45.

While we have particularly described and illustrated the best embodiments of our invention which are now known to us, it will be readily understood that many changes can be made in the form of our invention without departing from its spirit.

Having fully described our invention what we claim as new and desire to secure by Letters Patent, is:—

1. In a projector type of arc-lamp, the combination of a lens, three movable electrodes, a means for holding said three electrodes in substantially the same plane, the central one of the electrodes being in substantial alignment with the axis of the lens, the outer two inclined with respect to the central electrode, so as to cause the three electrodes to converge toward a common point substantially coincident with the axis of the lens, and a manually operable means for moving individually each of the three electrodes axially toward and away from the lens.

2. An arc-lamp for cinematographic, stereopticon or other projection purposes comprising a pantographic structure as a supporting means, three electrode carriers swung thereon, one being intermediate of the other two and sliding in a fixed support, electrodes mounted in said carriers, the outer electrodes converging toward the central electrode whereby a plurality of arcs may be formed simultaneously, guides controlling the direction of movement of the members of the pantographic structure and means for controlling the movement of the pantographic structure, electrode carriers, and therefore, also the three electrodes simultaneously, so that the latter will converge toward a common point.

3. A single phase system of carbon electrode arcs comprising three simultaneously movable electrodes arranged for convergence toward a common point whereby a plurality of arcs may be formed, means connecting the outer electrodes with two terminals of a source of single phase alternating current, and means connecting the intermediate electrode with a third terminal of said source intermediate the first-mentioned terminals.

In testimony whereof, we have signed this specification in the presence of two subscribing witnesses.
